UNITED STATES PATENT OFFICE.

LOUIS ZEVIN AND HARRY ZEVIN, OF NEW BRITAIN, CONNECTICUT.

CURTAIN AND SHADE-ROLLER HOLDER.

1,147,355.

Specification of Letters Patent.

Patented July 20, 1915.

Application filed June 20, 1913. Serial No. 774,804.

To all whom it may concern:

Be it known that we, LOUIS ZEVIN and HARRY ZEVIN, citizens of the United States, residing at New Britain, in the county of 5 Hartford and State of Connecticut, have invented certain new and useful Improvements in Curtain and Shade-Roller Holders, of which the following is a specification.

10 Our invention relates to improvements in curtain and shade roller holders, and the object of our improvement is simplicity and economy in construction and convenience and efficiency in use.

15 In the accompanying drawing:—Figure 1 is a front elevation of our improved curtain and shade roller holder, and a shade roller, a curtain pole, and part of a window casing. Fig. 2 is a front elevation on an enlarged scale of the left hand curtain and shade roller holder. Fig. 3 is an end elevation of the same. Fig. 4 is a sectional view on the line $\alpha\alpha$ of Fig. 2. Fig. 5 is a fragmentary view of the right hand shade 25 roller holder. Fig. 6 is a fragmentary view in part broken out of the curtain holder. Fig. 7 is a plan view of the curtain holder. Fig. 8 is a sectional view on the line $\gamma\gamma$ of Fig. 7. Fig. 9 is a plan view of part of 30 the blank for the separable element of the curtain holder. Fig. 10 is a front elevation corresponding to Fig. 1 and on the same scale of a modification of our curtain and shade roller holder and positioned on the 35 under side of the top cross-piece of the window casing. Fig. 11 is a similar view on the same scale as Fig. 2 of the left hand curtain and shade roller holder. Fig. 12 is an end elevation of the same.

40 Our curtain and shade roller holder comprises a pair of individual holders respectively a left holder 10 and a right holder 11 suitable for being secured to the window casing 12 and having adjustable means for 45 supporting a shade roller 13 and removable and adjustable means for supporting a pole 14 for a curtain.

The means for supporting the shade roller 13 comprise a left shade bracket 15 and a right shade bracket 16, and the means for supporting the curtain pole 14 comprise a pair of curtain brackets 17, and these means are supported in pairs on each side on a common base 18.

55 The left shade bracket 15 is provided with a slot 19 and the right shade bracket 16 is

provided with a hole 20 and which slot and hole are suitable for receiving the ends of the shade roller 13, otherwise the left and right shade brackets being quite similar.

60 The base 18 comprises an elongated rectangular plate like structure having a way 21 extending laterally along the front face of the body portion and which is bordered along the upper and lower edges 23 by strips 65 or raised portions 22 and which are undercut along the said edges 23. The base 18 is further provided with a hole 24, countersunk on the under side, positioned at about the middle of the way 21 and in which is secured the headed end of a clamping screw 25. A plurality of holes 56 for holding screws is also provided in the base 18.

70 The strips or raised portions 22 that form the way 21 terminate short of the outer end 75 of the base 18 so as to leave a clear space or platform 26 suitable for a seat for the curtain bracket 17. Positioned on the platform 26 and extending forwardly therefrom is a pair of studs 27 in vertical alinement, 80 and having enlarged heads 58 on the forward ends.

85 The shade brackets 15 and 16 comprise each a strip of sheet metal bent at right angles so as to form two arms, one of which, 28, is the base arm and serves as the supporting arm and which is a fit for the way 21 and is provided with a longitudinally extending slot 29 that is a fit for and suitable to receive the clamping screw 25. The 90 other arm 30 and 31 extends forwardly from the base arm 28 and is provided with the means for receiving the end of the shade roller 13 and which as stated is in the form of the slot 19 in the arm 30 of the left 95 holder 15 and in the form of the hole 20 in the arm 16 of the right holder 16. The base arm 28 has beveled upper and lower edges 32 suitable to engage with the undercut edges 23 of the way 21. The base arm 100 28 is slidably engaged in the way 21, the extent of the adjustment laterally being determined by the length of the slot 29. A clamping nut 33 engaged with the clamping screw 25 and bearing on the front face of 105 the base arm 28 serves to lock the base arm 28 in the position to which the same may be adjusted.

110 The curtain bracket 17 comprises as one element a vertical supporting arm 34 suitable for being seated on the platform 26 and having a pair of keyhole slots 35 suit-

able for engaging with the studs 27 so as to permit of being removably supported thereby. The key hole slots 35 comprise an enlarged portion or hole 36 at the lower end 5 and a relatively narrower or slot like portion 37 extending upwardly therefrom. The hole portion 36 is of sufficient size to pass over the head 58 of the stud 27 and the slot portion 37 is of less width than the said head 27, so that the upright supporting arm 34 may be engaged with the base 18 by slipping the holes 36 over the heads 58 and then drawing the supporting arm 34 downwardly so that the slot portion 37 will be positioned 10 in registration with the heads and the lateral walls thereof will be overhung by the said heads 58.

The details of the formation of the heads 58 and the lateral walls of the key hole slots 20 35 may be varied considerably without departing from the spirit of our invention.

The curtain bracket 17 comprises the supporting arm 34 at the rear and extending vertically and a forwardly extending pole 25 arm 38 extending forwardly from the upper end thereof and which serves as the support proper for the curtain pole 14, and is provided on the forward free end with means for engaging with and receiving the same, 30 and which as shown is in the form of an arc shaped loop or hook 39, open at the upper side. A cross brace 40 extends from the lower end of the supporting arm 34 forwardly and upwardly to the body portion of 35 the pole arm 38, and serves as a reinforcing brace therefor. The brace 40 is integral with the supporting arm 34 at the lower end and is provided at the upper end with a forwardly extending foot 41 positioned along 40 the under face of the pole arm 38 and which foot is provided with a hole 42 for a clamping screw 43. The pole arm 38 has a hole 44 for the said clamping screw 43 and the said clamping screw is provided with a clamping 45 nut 45. The clamping screw and nut 43 and 45 serve to clamp the free end of the brace 40 to the horizontal pole arm 38.

We prefer to have the pole arm 38 extensible, and in order to do this the said pole 50 arm 38 is made of two overlapping parts respectively an inner or rear part 46 and an outer or forward part 47. The inner part 46 extends forwardly from the upper end 55 of the supporting arm 34 and is formed integral therewith and the same extends over the foot 41 on the brace 40 and which is provided with the hole 42 for the clamping screw 43, already mentioned. Between the hole 44 and the vertical supporting arm 34 60 the inner part 46 is provided with a longitudinally extending slot 48. The forward part 47 comprises the pole loop or hook 39 at the front end and the body portion which overlaps the upper side of the forward portion 65 of the inner branch 46 and is provided

with a longitudinal slot 49 suitable to receive and in which is positioned the clamping screw 43 and the rear end has means for sliding engagement with the inner part 46 by means of the slot 48. The said latter 70 means comprise a downwardly directed branch 50 comprising a head 51 positioned across the slot 48 on the lower side of the inner part 46 and which is connected to the body portion of the forward part 47 by a 75 neck 52 which latter extends through the slot 48. The clamping nut 45 bridges the slot 49 in the forward part 47 and engages with the upper side of the said forward part 47, and when screwed onto the clamping screw 43 serves to lock the inner and outer parts 46 and 47 in the position to which they happen to be adjusted. The clamping screw 43 and nut 45 while serving to secure the overlapping parts 46 and 47 80 together as described also serves to hold the free end of the brace 40 to the composite arm 85 composed of the parts 46 and 47.

It will be noted that the parts 46 and 47 will be held against actual separation even 90 if the clamping screw and nut 43 and 45 are loosely connected and not actually locked, because the screw 43 serves to position the parts in overlapping engagement and the head 51 serves to positively prevent 95 the separation of the inner end of the forward part 47 from the body portion of the inner part 46.

In some cases it may be desired to support the shade roller 13^a within the window 100 casing 12 by placing the holders against the under side of the upper cross piece 53 there- 105 of, as in the case of the left holder 10^a, shown in Fig. 10, the mating right holder not being shown. In this case the curtain bracket 17 is dispensed with and the platform 26 is correspondingly omitted. Furthermore, as the shade roller arm 30^a is in pendent position the form of the slot 19^a 110 is changed accordingly, as shown in Fig. 12, 110 suitably to operatively receive the ordinary flattened left end of the shade roller 13^a. In this case the shade bracket 15^a is preferably positioned in the way 21 with the shade roller arm 30^a outward relatively to the 115 locking screw 25 so that in some cases if necessary the shade roller arm 30^a may be brought to position essentially flush with the lateral member 54 of the window casing 12.

As described, our curtain and shade roller holder comprises means for supporting shade roller brackets so as to permit of considerable leeway in the lateral adjustment thereof and also is provided with means for 125 removably supporting curtain brackets, and the said curtain brackets are so constructed as to permit of readily adjusting the relative forward position of the curtain pole.

The curtain bracket as described com- 130

prises a fixed member of triangular shape, composed of the upright supporting arm 34, the forwardly extending branch 46 constituting the inner member of the arm 38 and 5 the brace 40, all formed of one piece, having the ends overlapping and secured by the clamping screw 43 and nut 45, and also slidably secured to the slide member 47 constituting the forward part of the arm 38, and 10 the securing means therefor comprising in part the said clamping screw 43 and nut 45. Accordingly, the fixed member described is rigidly constructed and the slide member is positively connected thereto and by means 15 that permit of easy adjustment by manipulating a single clamping screw.

We claim as our invention:—

In a curtain holding device comprising a base and a curtain holder removably supported therefrom, the said curtain holder comprising a curtain arm having a horizontally extending supporting arm, the said bracket being formed of a single piece of 20 sheet metal in strip form, bent into triangular form, comprising one side extend-

ing horizontally, suitable to receive the said supporting arm, a second side extending downwardly from the rear end of the said first side, having means for being connected to the said base, and a third side extending 30 diagonally from the lower end of the said second side to the underside of the said first side, serving as a brace, a flange-like extension at the upper end of the said brace underlying the said first side, the said extension and first side having holes in registration and the said supporting arm having a slot in registration with the said holes, and a clamping screw passing through the said holes and also through the said slot and a 35 nut engaged with the said screw whereby the said clamping screw and nut serve to hold the ends of the said bracket together and also to secure the said curtain arm to the said bracket.
